Nelson N. Howard

UNITED STATES PATENT OFFICE.

WILLIAM R. FORSYTH, OF SWAMPCOTT, MASSACHUSETTS, ASSIGNOR TO UNITED SHOE MACHINERY CORPORATION, OF PATERSON, NEW JERSEY, A CORPORATION OF NEW JERSEY.

CUTTING BLOCK.

Application filed April 23, 1923. Serial No. 634,106.

To all whom it may concern:

Be it known that I, WILLIAM R. FORSYTH, a citizen of the United States, residing at Swampscott, in the county of Essex and 5 State of Massachusetts, have invented certain Improvements in Cutting Blocks, of which the following description, in connection with the accompanying drawings, is a specification, like reference characters on the 10 drawings indicating like parts in the several figures.

This invention relates to cutting blocks and, more particularly, to cutting blocks for use with presses employed in the cutting of 15 sheet material.

As commonly constructed, cutting blocks of the kind referred to comprise a relatively large number of block sections secured together in layers in such manner that the 20 grain of the wood is disposed substantially at a right angle to the cutting surface of the completed block. These block sections are bound together by side irons adjustably connected together so that the sections may be 25 firmly clamped in the desired relation to each other at the time of assembling the sections and so that the side irons may be subsequently adjusted if the necessity should arise to take care of shrinkage in the wooden 30 material of the block. In the past it has always been a difficult task, seldom if ever satisfactorily accomplished, to maintain a proper cutting surface on blocks used for wet work such, for instance, as that involved 35 in the cutting of raw rubber in sheets. In order to prevent the raw rubber from sticking to the block and to the dies it is customary to wet the rubber stock. This moisture spreads to the block and causes expansion 40 and subsequent contraction of various portions of the block and in varying degrees in the different portions so that the block often becomes distorted due to excessive expansion in certain parts of the block, followed 45 by looseness among the individual block sections upon shrinkage, since the side irons in these prior constructions are not sufficiently elastic to follow the blocks fully in their shrinkage. It not infrequently happens that the side irons are broken, due to 50 excessive expansion of the block, and where this does not occur the upper cutting surface "brooms" out during expansion and opens

up numerous cracks and crevices during the 55 subsequent shrinkage of the wooden fibres which make up the cutting surface of the block.

It is an object of this invention to provide a cutting block especially adapted for 60 the cutting of sheet material under conditions of expansion and contraction of the block including conditions which are likely to result in the application of moisture to the cutting surface of the block.

To this end the block is provided with 65 improved retaining members adapted to yield upon expansion of the block or any part thereof and to maintain proper pressure on all portions of the block during contraction thereof due to shrinkage in the block 70 material.

In the illustrative block the retaining members are connected with each other in such a manner as to permit of expansion of 75 the block both longitudinally and transversely thereof, the arrangement being such that all portions are equally free to expand. An important feature of the block relates to the provision of means for insuring that the retaining members retain their efficiency 80 during the shrinkage of the block or of any part thereof through an elasticity which causes the retaining members to follow up the block portions at all times during shrinkage to hold the latter firmly clamped and thus avoid the opening up of cracks or 85 crevices in the cutting surface of the block. As shown, each individual cross bar extending transversely of the block is provided with spring means for retaining the adjacent 90 portions of the block under yielding pressure. The provision of a relatively large number of these cross bars, preferably spaced rather closely with respect to each other, is an important factor in maintaining 95 an effective cutting surface on all parts of the block. Similarly the illustrated block has end spring means which follow up the block portions at all times during longitudinal contraction of the block.

Other features of the invention and novel combinations of parts will be described in the detailed specification and pointed out in the appended claims.

In the drawings, 100
Fig. 1 is a plan view showing a cutting

block in position on the bed of a clicking machine;

Fig. 2 is a plan view of a cutting block showing another species of the invention; 5 and

Fig. 3 is a detail view of the end of one of the side bars of the block shown in Fig. 2.

Referring to Fig. 1 of the drawings, it will be observed that the cutting block 4, 10 below the presser arm 5 of the clicking machine, is made up of rows or layers of small blocks or sections 6 placed in close juxtaposition to each other and made of various sizes so that they may be readily 15 arranged to break joints between the various sections. It will be understood that the blocks have been cut across the grain of the wood and arranged so that they stand with the grain of the wood 20 substantially perpendicular to the cutting surface of the completed block. For retaining the block sections in their properly assembled relation there is provided a set of retaining frame members indicated in general by the reference character 25 8. These retaining members include the rear side bar 10, the end bars 12, and the front side bar 14. As clearly indicated in the drawing, the ends of the bar 14 pass 30 with a close fit through perforations in the corresponding ends of the end bars 12. On the contrary, the bar 10 has its ends passing through elongated slots 15 in the other ends of the end bars 12. Since the end bar at the 35 right end of the block in Fig. 1 may slide freely on the ends of the side bars 10 and 14, expansion of the block in a direction longitudinally thereof is freely provided for. Similarly, expansion of the block in a direction 40 transversely thereof may take place freely since the side bar 10 is movable with respect to the end bars 12 in a direction lengthwise of the slots 15.

As heretofore stated, means is provided 45 for resisting the expansion of the block and for following up the block as it shrinks subsequently to expansion so as to retain the block constantly under pressure in all directions, thereby preventing the opening up 50 of cracks or crevices between the small blocks or sections which constitute the cutting block. In the block shown in Fig. 1, there is interposed between the ends of the side bars 10 and 14 and one of the end bars 55 12 a relatively heavy spring member 16 which thus constitutes a single spring means common to the two side bars 10 and 14 and which is operative to resist yieldingly longitudinal expansion of the block. Each side bar 10, 14 passes through a slot 17 in the corresponding end of the spring 16 and is provided with a washer 18 and a retaining nut 20 screw-threaded upon the end of the bar so that the tension of the spring 16 may 60 be adjusted as desired or required by the 65

particular conditions under which the block is being used. Passing transversely through the block 4 is a plurality of rods or bars 30, 34, of which the bars 30 are placed closely adjacent each end of the cutting block 4 for a purpose that will be presently described. 70 These cross bars are preferably extended through the cutting block along the plane formed between two adjacent rows of block sections so that the perforation for the rod is formed of two grooves, one in each surface of the opposed layers of blocks, the purpose being to have the rods so positioned that they will not be affected by the expansion 75 and contraction of the individual sections. For contacting with the side bar 14 each rod 30, 34 is provided with a relatively large rounded head presenting a smooth surface so that there is no obstruction or dangerous 80 projecting part at the front of the block 85 where the workman stands. These heads of the bolts are relatively large so that they may engage firmly on opposite sides of the elongated slots through which the bolts pass in the side bar 14, the purpose of the slots 90 being to permit of expansion of the block 95 in its longitudinal direction without hindrance from the transverse bolts 30, 34. At the opposite end, each bolt 30, 34 projects a considerable distance beyond the side bar 10 100 in order that a spring 38 may be interposed between the retaining nut 40 and the adjacent surface of the side bar 10. These springs 38, one for each cross bar, 30, 34 105 serve to retain the side bar 10 yieldingly in contact with the cutting block 4 during expansion and contraction of the block in a direction transversely thereof. As before stated, the bolts 30 are closely adjacent to each end of the cutting block so that the 110 yielding means designed to compensate for expansion and contraction transversely of the block may operate closely adjacent to the ends of the block as well as at points intermediate between the ends of the block. It 115 will be understood that another form of spring may be substituted for the leaf spring shown at 38, but the latter is preferred since it secures pressure at two points spaced at a considerable distance from each other on each side of each cross bar 30, 34.

In the species shown in Fig. 2 of the drawings, the end bars 50 and 52 pass through openings in the side bars 54 and 56 respectively. This change over the construction shown in Fig. 1, wherein the side bars 10 and 14 pass through openings in the ends of the end bars 12, has the advantage of permitting the use of springs 58 at the ends of the end bars 50, 52 so that spring pressure 120 is applied at the very end portions of the block to resist expansion of these portions of the block in a transverse direction. It will be observed that the end bar 52 passes 125 snugly through openings in the ends of the 130

bars 54, 56 whereas the end bar 50 passes through elongated slots 60 in the ends of the side bars 54, 56. Thus, expansion of the block 64 in a longitudinal direction is taken up through movement of the end bar 50 against the pressure of the spring 66, the spring being mounted on the ends of the side bars 54, 56 which pass through slots 67 in the ends of the spring and support adjusting means such as the nuts and washers 18 and 20. For taking care of expansion and contraction in a direction transversely of the block the side bar 56 is mounted for movement in a direction toward and from the side bar 54, bar 56 being slidably mounted upon the end bars 50, 52 and also upon the rods or bolts 68. For retaining the bar 56 yeldingly against expansive movement of parts or portions of the block 64 there is interposed between adjusting members 69 on the ends of the bolts 68 and the adjacent surfaces of the side bar 56 springs 70 similar in all respects to the springs 38 in the species of the invention disclosed in Fig. 1. In addition, helical springs 72 may be provided in which case each bolt 68 has the effect of applying pressure yeldingly at three points upon the adjacent surfaces of the side bar 56.

It will be noted that the invention, generically considered, involves the use of retaining members or a frame work in which the more or less elastic members engage on every side of the cutting block, and spring members which permit expansion of the block and which cause the frame-work or retaining members to clamp firmly and follow up the shrinking block, said spring members being arranged to operate upon the retaining members and not upon the block directly. By this arrangement the individual sections which comprise the cutting block are maintained in alinement with adjacent sections with provision, however, for more or less local expansion against the yielding resistance afforded by the elastic side irons and the yielding spring members provided for each relatively restricted portion of the block. It is obvious that in the operations of cutting wet rubber stock it is likely to occur that some certain portion or portions of the block will receive more moisture than other portions and hence that greater expansive and contractive movements will take place in some localities of the block than in other portions thereof. Through the provision of relatively numerous transverse bolts carrying spring members for co-operation yeldingly with the retaining side members, these inequalities in the expanding and contracting movements of various portions of the block are readily taken care of, and the block as a whole maintained properly clamped with the adjacent sections in good contact, thereby avoiding the opening up of seams or crevices which would render the

block less serviceable or even destroy its usefulness.

It will be understood that the clamping or retaining frame is not limited in its use to the special sectional block shown in the drawings nor to what is known generically as a sectional die block, it being obvious that the clamping frame herein disclosed may be used with any block subject to expansive and contractive movements of portions thereof during periods of use and disuse.

Having thus described my invention, what I claim as new and desire to secure by Letters Patent of the United States is:—

1. A clamping frame for a cutting block comprising interconnected side and end clamping members for exerting pressure on the block in directions both longitudinally and transversely of the block, and spring members for applying yielding pressure upon all sides of the block.

2. A clamping frame for a cutting block comprising interconnected side and end clamping members for exerting pressure on the block in directions both longitudinally and transversely of the block, a spring member for applying yielding pressure in a direction longitudinally of the block, and a spring member for applying yielding pressure transversely of the block.

3. A clamping frame for a cutting block comprising interconnected side and end clamping members for exerting pressure on the block in directions both longitudinally and transversely of the block, a spring for bearing upon the clamping member at one end of the block, and a spring for bearing upon a clamping member located at a right angle to the end clamping member.

4. In a device for clamping the sides and ends of a cutting block, clamping members at opposite ends and sides of the block and connected to each other to provide a clamping frame for the block, a spring member connected to the ends of the side clamping members to exert pressure upon the end clamping members, and a spring member for exerting pressure upon the side clamping members to resist yeldingly expansion transversely of the block.

5. In a device for clamping the sides and ends of a cutting block, clamping members at opposite ends and sides of the block and connected to each other to provide a clamping frame for the block, a spring member connected to the ends of the side clamping members to exert pressure upon the end clamping members, and a plurality of spring members for exerting pressure upon the side clamping members to resist yeldingly expansion transversely of the block.

6. In a cutting block comprising a plurality of wooden sections arranged to provide an even cutting surface for the block, side and end clamping members connected to

- each other around the block to provide a clamping frame therefor, a spring means connected to the ends of the side clamping members for exerting pressure upon the end clamping members to resist expansion longitudinally of the block, and spring means for exerting pressure upon the side clamping members to resist expansion transversely of the block.
- 10 7. In a cutting block comprising wooden sections clamped together and arranged to provide an even surface for cutting operations upon sheet material, clamping members for holding the sections together comprising side clamping members and end clamping members for the block, one of said clamping members passing loosely through the adjacent ends of a pair of the other clamping members, and spring means for pressing each clamping member toward the clamping member opposed thereto.
- 15 8. In a cutting block comprising sections clamped together to provide an even surface for the cutting block, side and end clamping members connected to each other around the block, a spring member connected to the ends of the side clamping members at one end of the block to exert pressure upon the end clamping members, a plurality of bars 70 passing transversely through the block, and spring members associated with the bars for pressing upon the side clamping members to resist expansion of the block in a transverse direction.
- 20 9. In a cutting block comprising sections clamped together to provide an even surface for the cutting block, side and end clamping members connected to each other around the block, a spring member connected to the ends of the side clamping members at one end of the block to exert pressure upon the end clamping members, a plurality of bars 75 passing transversely through the block, and a leaf spring associated with each bar for pressing upon the side clamping members to resist expansion of the block in a transverse direction.
- 25 10. In a cutting block, side and end clamping members for exerting pressure on the block in directions both longitudinally and transversely of the block, and means for applying yielding pressure to the block to permit expansion and to maintain pressure during contraction thereof.
- 30 11. In a cutting block, side and end clamping members for exerting pressure on the block in directions both longitudinally and transversely of the block, said end clamping members comprising bars slotted to receive the ends of the side clamping members, and a spring member connected to the projecting ends of the side clamping members and arranged to exert pressure on the end clamping members.
- 35 12. In a cutting block, side and end clamping members for exerting pressure on the block in directions both longitudinally and transversely of the block, one of said side clamping members being arranged to pass through elongated slots in the ends of the end clamping members so that it may move laterally relatively to the other side clamping member, cross bars connecting the side clamping members, and springs on the ends of the bars arranged to exert pressure 80 upon the side clamping members yieldingly to resist expansion of the block transversely thereof.
- 40 13. In a cutting block, clamping members at opposite ends and sides of the block and connected to each other to provide a clamping frame for the block, and spring means co-operating with the clamping members so that the block is free to expand.
- 45 14. In a cutting block, clamping members at opposite ends and sides of the block and connected to each other to provide a clamping frame for the block, and spring members co-operating with the clamping members so that the block may expand both 85 laterally and longitudinally.

In testimony whereof I have signed my name to this specification.

WILLIAM R. FORSYTH.
